UNITED STATES PATENT OFFICE.

GEORGE W. ELSEY, OF ANDERSON, INDIANA, ASSIGNOR, BY MESNE ASSIGNMENTS, TO DELCO-REMY CORPORATION, OF DAYTON, OHIO, A CORPORATION OF DELAWARE.

ENGINE-STARTING APPARATUS.

Application filed July 11, 1924. Serial No. 725,522.

This invention relates to electrical starting apparatus for internal combustion engines, and particularly to the type of apparatus which includes an electric motor operating a motor pinion normally out of engagement with an engine gear and movable into engagement with said gear for the purpose of cranking the engine.

The objects of the present invention include meshing the pinion with the engine gear by manual operation, and demeshing the pinion automatically when the engine starts, regardless of the status of the member which is manipulated by the operator.

These objects are accomplished in the present invention by employing a spirally-splined motor-driven shaft along which the pinion, threadedly connected to the shaft, is endwise movable into mesh with the engine gear. A pedal having a yielding connection with a pinion-shifting device is operated to move the pinion into mesh with the engine gear. Due to the spiral-spline connection of the pinion and shaft, the pinion is automatically demeshed when the engine starts. The yielding connection permits demeshing the pinion regardless of failure to release the pedal; and a latch, rendered operative by movement of the pedal to position to close the motor switch, engages the pinion-shifting device, as the pinion is demeshed, to hold the pinion out of engagement with the engine gear while the pedal is retained in operating position.

Return of the pedal to normal position releases the latch from the pinion-shifting device so that the starting operation can be repeated.

Further objects and advantages of the present invention will be apparent from the following description, reference being had to the accompanying drawings, wherein a preferred form of embodiment of the present invention is clearly shown.

55 In the drawings:

Fig. 1 is a fragmentary side view, partly in section, showing a form of the invention, the parts being in normal position.

Fig. 2 is a view similar to Fig. 1 showing parts in engine-cranking position; and

Fig. 3 is a sectional view on the line 3—3 of Fig. 1.

The internal combustion engine is not

shown but is represented by a flywheel gear 20 adapted to be driven by and drive a motor pinion 21 threadedly connected with the spirally splined portion 22 of the motor shaft 23 which is journaled in suitable bearings provided by the housing 24 and by an end frame (not shown) attached to the left hand end of the motor field frame 25. The shaft 23 carries a stop collar 26 pinned to the shaft for receiving the thrust of the motor pinion 21. Thrust washers 27 are located between the collar 26 and a plane surface 28 provided by the housing 24. Housing 24 supports a rod 30 providing a pivot for the forked lever 31 received by a groove 32 which is defined by flanges 33 and 34 extending from the hub 35 of the motor pinion 21.

The mechanism for shifting the lever 31 includes a pedal 40 attached to a rod 41 which is connected with a lever 42 rotatable about the rod 30. For maintaining the pedal 40 in normal position shown in Fig. 1, there is provided a spring 43 located between the pedal 40 and a cup-shaped member 44 which encircles the rod 41 and is supported by the floor board 45 of the automobile. The lever 42 is connected with the lever 31 by a spring 50 which is coiled around the rod 30. One end 51 of the spring 50 slidably engages a hole provided in a stud 52 attached to the lever 31. The other end 53 of spring 50 slidably engages a hole 54, see Fig. 3, of a bolt 55 which is adjustably connected with the lever 42. To provide this adjustment the lever 42 is provided with a slot 56 for receiving the threaded shank 57 of the bolt 55. The spring 50 is initially adjusted by moving the spring bolt 55 along the slot 56. The bolt 55 is secured in adjusted position by the nuts 58.

The lever 42 carries an adjustable screw 60 for engaging the plunger 61 of a motor switch 62, secured to the motor frame 25 by screws 63. The plunger 61 is moved by the operation of the pedal lever 42 and screw 60 into the position shown in Fig. 2 whereupon a movable contact within the switch case is moved into engagement with the stationary contacts not shown, the one being connected with the motor field circuit and the other with the switch terminal 64 for connecting the motor switch with a battery

or other current source. A spring 65 restores the plunger 61 into switch opening position.

To start the engine the pedal 40 is depressed causing the lever 42 to move downwardly. Motion to the lever 31 is transmitted from the lever 42 through the spring 50, causing the lever 31 to move counter-clockwise and the pinion 21 to move to the right into engagement with the flywheel gear 20. In case the teeth of the pinion 21 abut the teeth of the gear 20, thereby arresting movement of the lever 31, motion of the pedal 40 is continued so that the screw 60 will engage the plunger 61 and close the motor switch. The motor will then rotate the shaft 23 to cause the pinion 21 to register with the tooth spaces of the gear 20. When this occurs, the spring 50 will quickly move or "jump" the pinion 21 into engagement with the gear 20.

When, by virtue of pedal operation, the pinion 21 has been brought into substantial engagement with the gear 20, the operation 25 of the motor, due to closing the switch 62, will cause the pinion 21 to be rotated into complete engagement with the gear 20 and against the stop collar 26, then the motor will crank the engine.

30 After the engine has become self-operative, the pinion 21 will be automatically disconnected from the engine gear due to the superior rotation of the engine gear 20 relative to the rotation of the pinion 21, and 35 due to the spiral splined connection of the pinion 21 and shaft 23. While the pedal 40 is depressed, demeshing of the motor pinion 21 is resisted by the spring 50. To prevent the return of the pinion 21 into contact with 40 the engine gear 20 there is provided a device which includes a pawl 70 pivoted at 71 upon a bracket 72 attached by screws 73 to the housing 24. The pawl 70 is adapted to engage a notch 75 provided by the lever 31. 45 The lever 42 carries a pin 76 for engaging the pawl 70 and maintaining the pawl out of the line of motion of the notch 75 while the pinion 21 is being moved by the lever 42 into engagement with the flywheel gear 20. Fig. 2 shows the lever 42 in position 50 for closing the motor switch, and the pin 76 has been retracted from the pawl 70 to permit a spring 77, connecting the bracket 72 with the pawl 70, to yieldingly urge the 55 pawl 70 against the surface 78 of lever 31.

When the engine becomes self-operative and accelerates very rapidly, the pinion 21 will be thrown to the left with force sufficient to cause the lever 31 to move into the position 31^a indicated by dot and dash lines. The movement will be sufficient to retract the surface 78 from the pawl 70 and permit the end of the pawl to be drawn by spring 77 into the notch 75. Therefore the lever 31 will be retained in this position and the

pinion 21 out of contact with the gear 20 although the pedal 40 may still be held in engine cranking position. The latching position of the pawl 70 is indicated in Fig. 2 at 70^a.

70 Release of the pedal 40 allows the spring 43 to return the lever 42 to normal position shown in Fig. 1, causing the spring 50 to be relieved and the pin 76 to engage the pawl 70 and move it into an inoperative 75 position. The spring 65 being released by release of pedal 40, the switch plunger 61 will be returned to normal or switch opening position.

80 In case the engine fails to start after being connected with the motor in the manner described, the failure of the motor pinion 21 to come out of mesh with the engine gear will not prevent the release of the pedal 40 and the disconnection of the motor from a 85 source of current.

90 It is apparent from the foregoing description that the present invention embodies a starting apparatus which is exceedingly simple in construction, therefore the cost of manufacture has been materially reduced.

95 While the form of embodiment of the present invention as herein disclosed, constitutes a preferred form, it is to be understood that other forms might be adopted, 100 all coming within the scope of the claims which follow.

What is claimed is as follows:

1. Engine starting apparatus comprising, 100 in combination, a pinion adapted to engage and drive an engine gear and to be driven thereby when the engine becomes self-operative; of a motor; a spirally splined shaft operated by the motor and threadedly connected with the pinion whereby, when the 105 engine drives the pinion, the pinion will be automatically demeshed; a lever for shifting the pinion into mesh with the engine gear; a controlling member for rendering the motor operative; a spring connecting said 110 member and said lever whereby the latter is moved by movement of the member, and demeshing of the pinion is permitted regardless of the status of the control member; a device for latching the lever in pinion non-meshing position if the member is held in 115 operating position when the engine becomes self-operative; and means for unlatching said lever by the return of said member to normal position.

120 2. Engine starting apparatus comprising, in combination, a pinion adapted to engage and drive an engine gear and to be driven thereby when the engine becomes self-operative; of a motor; a spirally splined shaft 125 operated by the motor and threadedly connected with the pinion whereby, when the engine drives the pinion, the pinion will be automatically demeshed; a lever for shifting the pinion into mesh with the engine 130

gear; an operating lever for rendering the motor operative; a spring connecting said levers whereby the pinion is shifted into mesh with the engine gear by the movement 5 of the operating lever, and demeshing of the pinion is permitted regardless of the status of the operating lever; a latch pawl; means connected with the operating lever for normally holding the pawl out of contact with 10 the shifting lever and for permitting the

pawl to move into contact with the shifting lever when the operating lever is moved into position to start the motor, said shifting lever having a notch for receiving the pawl to retain the shifting lever in non-operating 15 position in case the control lever is held in operating position after the engine starts.

In testimony whereof I hereto affix my signature.

GEORGE W. ELSEY.
